CLAIM

The ornamental design for a seat belt buckle cover, as shown and described.

DESCRIPTION

FIG. 1 is a top perspective view of the seat belt buckle cover according to a first embodiment of my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top perspective view of the seat belt buckle cover according to a second embodiment of my design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a top perspective view of the seat belt buckle cover according to a third embodiment of my design;

FIG. 16 is a front elevation view thereof;

FIG. 17 is a rear elevation view thereof;

FIG. 18 is a right side elevation view thereof;

FIG. 19 is a left side elevation view thereof;

FIG. 20 is a top plan view thereof; and,

FIG. 21 is a bottom plan view thereof.

Broken lines are environmental only and form no part of the claimed design. The break lines shown in FIGS. 15-19 symbolize a break in the length of the article in which the claimed design is embodied. The appearance of any portion of the article between the break lines forms no part of the claimed design
